US00D904383S

(12) **United States Design Patent** (10) **Patent No.:** **US D904,383 S**
Kim (45) **Date of Patent:** **** Dec. 8, 2020**

(54) **CASE FOR ELECTRONIC COMMUNICATIONS DEVICE**

(71) Applicant: **SPIGEN KOREA CO., LTD.**, Seoul (KR)

(72) Inventor: **Seungjoo Kim**, Seoul (KR)

(73) Assignee: **Spigen Korea CO., LTD.**, Seoul (KR)

(**) Term: **15 Years**

(21) Appl. No.: **29/696,676**

(22) Filed: **Jun. 28, 2019**

(51) **LOC (12) Cl. 14-03**

(52) **U.S. Cl.**

USPC **D14/250**

(58) **Field of Classification Search**

(74) *Attorney, Agent, or Firm* — Heedong Chae; Lucem, PC

(57) **CLAIM**

The ornamental design for a case for electronic communications device, as shown and described.

DESCRIPTION

FIG. 1 is a front perspective view of the case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line and the unshaded interior region delineated by the broken line in FIG. 1 forms no part of the claimed design.

1 Claim, 8 Drawing Sheets
